UNITED STATES PATENT OFFICE.

HARRY H. NORTON, OF NEW YORK, N. Y.

DESIGN FOR AN AUTOMOBILE LAMP.

60,755.

Specification for Design.

Patented Apr. 4, 1922.

Application filed December 18, 1920. Serial No. 431,780. Term of patent 3½ years.

To all whom it may concern:

Be it known that I, HARRY H. NORTON, a citizen of the United States, residing at New York city, in the county of New York and State of New York, have invented certain new, original, and ornamental Design for Automobile Lamps, of which the following is a specification, reference being had to accompanying drawing in which—

Figure 1 is a view of the lamp in side elevation, showing my design.

Figure 2 is a view in end elevation of the front end of the lamp, and

Figure 3 is a view in end elevation of the rear end of the lamp.

The lamp is cylindrical in configuration

and having a dull black body with a highly polished back and a polished annular rim at its front end to support the lens. The side of the body is cut-away and a pane of glass, beveled as shown is inserted therein.

Having thus described my design, what I claim and desire to secure by United States Design Letters Patent is:—

The ornamental design for an automobile lamp as shown.

In testimony whereof I affix my signature in presence of two witnesses.

HARRY H. NORTON. [L.S.]

Witnesses:

HENRY BURNETT,
W. BUNDY COLE.
